J. D. PEDERSEN,

FIREARM.

APPLICATION FILED DEC. 17, 1919.

1,355,425.

Patented Oct. 12, 1920.

8 December:
John D. Pedersen,
By his Atty, T. W. Richards,

UNITED STATES PATENT OFFICE.

JOHN D. PEDERSEN, OF JACKSON, WYOMING.

FIREARM.

1,355,425.

Specification of Letters Patent. Patented Oct. 12, 1920.

Application filed December 17, 1919. Serial No. 345,551.

To all whom it may concern:

Be it known that I, JOHN D. PEDERSEN, a citizen of the United States, residing in Jackson, in the county of Lincoln and State 5 of Wyoming, have invented certain new and useful Improvements in Firearms, of which the following is a specification.

This invention relates more especially to that class of firearms which is usually designated as small arms, and a principal object 10 of the invention is to furnish an improved grip-safety device particularly applicable to auto-loading and automatic-pistols.

One class of small arms to which my present 15 improvements are applicable, includes the auto-loading pistols having a grip-stock or handle-portion of the frame or receiver of the firearm, which is adapted to receive a safety device operable by hand grip or 20 compression.

An improved auto-loading pistol of this kind is described in my copending (renewal) application Serial No. 311,689, filed July 17, 1919. Therefore, for convenience 25 of illustration, I have herein shown my present improvements as arranged and applied to the particular kind of auto-loading pistol which is shown in the drawings of said application, to which reference may be 30 had.

The features of my grip-safety device are that it is a grip, or handle contained, safety device arranged to prevent discharge of the firearm by locking the firing member or 35 hammer and the trigger-sear, when my grip-safety device is in normal position or position of safety.

Also, where the firearm is provided with a sliding breechaction comprising a firing-pin to prevent discharge of the firearm by 40 locking the breechaction to prevent contact between the firing-pin and the cartridge so that action of the firing member or hammer on the firing-pin will not explode the cartridge, this being accomplished by a member which blocks a shiftable sliding member or controller in position to lock such sliding breechaction when my grip-safety device is 45 in normal position or position of safety, 50 said blocking member being actuated by a grip-operable member, the shiftable shiftable controller being releasable from position locking the breechaction by grip-compression of the grip-operable member which 55 moves the blocking member so that engagement of the trigger member with the sear

member will move the sear member to release the firing member or hammer from movement from firing position to fired position, and at the same time shift the shiftable member or controller out of locking position into position releasing the sliding breechaction and permitting discharge of the firearm. 60

In the accompanying drawings, which 65 illustrate an embodiment of my grip-safety device,

Fig. 1 is a side elevation, partly broken away to show the details, of a pistol provided with my grip-safety device, the grip-operable member or grip-safety member thereof being in normal position or position of safety, the sliding breechaction of the pistol being locked, and the firing member or hammer being in firing position. 70

Fig. 2 is a fragmentary side view, on larger scale than Fig. 1, of the rear portion of a pistol, showing the details, the grip-operable member or grip-safety member thereof being grip-compressed, and the blocking member being moved to position for release of the sliding breechaction of the pistol by movement of the shiftable shiftable member or controller due to pressure of the trigger-member, the firing member 85 or hammer being in firing position. 75

Fig. 3 is a fragmentary side view on substantially the same scale as Fig. 2, showing the details of the rear end of a pistol provided with my grip-safety device, the grip-operable member or grip-safety member being grip-compressed, and the shiftable shiftable member or controller being released from the blocking member and moved to release the sliding breechaction of the pistol, 90 and the sear member moved to release the firing member or hammer, by pressure on the trigger member, the firing member or hammer being in fired position. 95

Fig. 4 is a front end sectional view, on the line 4-4 of Fig. 3, looking in the direction of the arrow, showing the details of the rear end of a pistol provided with my grip-safety device, a front end portion of the grip-stock of the pistol being removed, 105 and the shiftable shiftable member or controller being in position for locking the sliding breechaction of the pistol. 100

Similar reference characters or numerals refer to similar parts throughout the several views. 110

My grip-safety device, generally denoted

- by G, comprises a grip-operable member or grip-safety member G'. The grip-safety member G' is attached at the lower end thereof by a pivot-pin *g* to the grip-stock 5 of the pistol, the grip-stock of the pistol being bored or otherwise cut away at 2° to receive the grip-safety member G'. The upper end G² of the grip-safety member G' is engageable with the frame of the pistol, 10 the grip-safety member G' being hand compressible or yieldable. The grip-safety member G' closes the slot or space 2^a, which slot or space is of use in assembling the details of my invention.
- 15 The firing member or hammer H is pivotally attached to the grip-stock of the pistol and is movable to firing position and to fired position. The firing member or hammer H is provided with a firing-notch or 20 cock-notch 8^j and with an eccentric cam face 8^k.

The shiftable slidable member or controller N is located at its upper end in an opening 10 in the frame or receiver of the 25 pistol, and is movable upwardly and downwardly. The slidable member or controller N is provided at its upper end with a point or face 14^a, which, when the shiftable slidable controller is in upward position, lies in 30 the path of or blocks the sliding breechaction of the pistol in its movement.

The shiftable slidable member or controller is provided with a shoulder 14^b having an upper engaging surface 14^c. A recess or slot 11, is provided in the shiftable slidable member or controller to receive the end of the trigger member F, and permit movement or play upward and downward 35 of the trigger member F therein.

40 The lower portion of the shiftable slidable member or controller terminates in a recess which affords a front face 12, and end face or bottom side 13 and an end point 14.

The shiftable slidable member or controller N is provided with a spring operated actuator 14^d to move the shiftable slidable member or controller upwardly.

45 The lever member n is pivotally attached to the shiftable slidable member or controller N, and is provided with a face for engaging the actuator 14^d, and with an end for engaging the sear member S.

The sear member is pivotally attached to the grip-stock of the pistol, and is provided 50 with a shoulder 17^b for engaging the firing-notch or cock-notch 8^j of the firing member or hammer H, and with a face 17^a for engaging the eccentric cam face 8^k of the firing member or hammer, and with an arm S¹⁰ 55 having a face 17^c for engaging the upper surface 14^e of the shiftable slidable member or controller and with a lever-face 17^e for engaging the end of the lever member n. The lower end 17^d of the sear member S is

engageable with the end of the trigger member F.

The blocking member or controller-blocking member 16, is pivotally attached at its lower end to the grip-stock of the pistol by a pivot-pin 17, and is provided with a 70 slightly extended face 18, which engages the grip-operable or grip-safety member G', so that grip-compression of the member G' will move pivotally or rock the blocking member 16, when the member G' is grip-compressed. The blocking member or controller-blocking member 16, is provided at its upper end with an end-face 19 which is engageable with the end-face or bottom-side 13 of the shiftable slidable member or controller N to retain the shiftable slidable member or controller in upward locking position, and with a recess which affords a rear-face 20 with which said end-point 14 of the shiftable slidable member or controller N is engageable to prevent the end-face or bottom-side 13 from slipping outwardly or forwardly out of engagement with the end-face 19 of the blocking member.

90 The rod 21 is pivotally attached at its upper end to the firing member or hammer H, and is pivotally attached at its lower end to the blocking member or controller-blocking member 16, the rod 21 being provided with upper and lower abutments or stop-faces 22 and 23.

95 The spring 8^e surrounds the rod 21, the spring 8^e being seated on the lower abutment or stop-face 23, and at its upper end abutting the upper abutment or stop-face 22, the tendency and purpose of the spring 8^e primarily being to move the firing member or hammer H to fired position.

100 When the firing member or hammer H is in firing position, a line from the center of pivotal attachment of the rod 21 to the firing member or hammer through the center of pivotal attachment of the rod 21 to the blocking member 16, will pass to the rear 110 of the center of pivotal attachment of the grip-operable or grip-safety member G' to the grip-stock, the spring 8^e thus affording grip-compression of the member G' and returning the end G² of the member G' to engagement with the grip-stock after grip-compression. When the firing member or hammer H is in fired position, a line from the center of pivotal attachment of the rod 21 to the firing member or hammer, through the center of pivotal attachment of the rod 21 to the blocking member 16, will pass in front of the center of pivotal attachment of the grip-operable or grip-safety member G', the tendency of the spring 8^e then 115 being to hold the grip-operable or grip-safety member in forward position, and thus to neutralize the reaction or sting of

the spring 8^e upon the member G' due to sudden arresting of the firing member or hammer H when actuated by the spring 8^e.

The trigger member F is movable forwardly by means not shown, and by pull thereon is movable rearwardly. The inner end of the trigger member F is attached to the shiftable slidable member or controller N, by a pivot pin 24, the trigger member being received in the slot 11, and movable upwardly and downwardly therein. The trigger member F is provided with an inclined end-face 25, which is engageable when the trigger-member is pulled or moved rearwardly with the end-face 17^a of the sear member S to move the sear member.

The grip-operable member G' is provided at its upper end with stop means or detent 26, which prevents outward or rearward movement of the member G' at its upper end, and prevents rearward movement of the blocking member 16, when the grip-operable member is in position of safety, and suitable means 27, is provided to limit the forward movement of the blocking member 16, when the grip-operable member is grip-compressed.

In operation, when my grip-safety device is in normal position or position of safety, the firing member or hammer H is in firing or cocked position, Fig. 1, and locked in this position by the sear member S, and cooperation therewith of the lever member n, and actuator 14^m, the shiftable slidable member or controller N being in upward position, and so held by the blocking or controller-blocking member 16, and grip-safety member G', the end 14^a of the shiftable slidable member or controller locking the sliding breechaction of the pistol against movement.

The shiftable slidable member or controller N is moved to this upward position by movement of the firing member or hammer H to firing or cocked position, the cam face 8^k of the firing member or hammer engaging the face 17^a of the sear member S to move the sear member, the lever face 17^a of which engages the end of the lever member n, the face of which engages the actuator 14^m, which moves the shiftable slidable member or controller N upwardly.

The end G² of the grip-operable or grip-safety member G', Fig. 1, is in engagement with the frame of the pistol and is in normal position or position of safety. The face 18 of the blocking member or controller-blocking member 16 is in engagement with the grip-safety member G', and the end-face 19, of the controller-blocking member 16 is in engagement with the end-face or bottom side of the shiftable slidable member or controller N, thereby locking the shiftable slidable member or controller in upward position.

65 Grip-compression of the grip-safety mem-

ber G', Figs. 2 and 3, disengages the end G² thereof from the frame of the pistol and moves or rocks the blocking member or controller-blocking member 16, forwardly so that the end-face 19 thereof is moved forwardly on the end-face or bottom side 13 of the shiftable slidable member or controller N, but not sufficiently to be entirely out of engagement therewith, the end-face 19, being of sufficient width to contact with the rib 27, of the grip-stock and prevented from further outward movement. Suitable detent means other than the rib 27, may be provided for this purpose.

Pull upon the trigger-member F, while the grip-operable or grip-safety member G' is grip-compressed, shifts the lower end of the shiftable slidable member or controller N inwardly and thereby releases the end-face or bottom-side 13 thereof out of engagement with the end-face 19 of the blocking member 16, and permits downward movement of the shiftable slidable member or controller from locking position, and also, by engagement of the inclined end-face 25 with the end 17^a of the sear member S, moves the sear member to release the firing member or hammer H for movement to fired position.

Movement of the sear member S also engages or brings into contact, by movement of the firing member or hammer H to fired position, the end 17^a of the arm S¹⁰ thereof with the upper surface 14^e of the shoulder 14^p of the shiftable member or controller N, Fig. 3, thus moving the shiftable slidable member or controller downwardly, and thereby releasing the sliding breechaction and permitting discharge of the pistol upon contact of the firing member or hammer H with the firing pin of the sliding breechaction.

Having thus described my invention, I claim:

1. In a firearm, in combination, a frame 110 comprising a grip-stock, a firing member movable to firing position and to fired position, sear means engageable with said firing member, shiftable slidable means, means for moving said shiftable slidable means in direction to lock said sear means and firing member in firing position, means for moving said shiftable slidable means in a reverse direction when said firing member is moved to fired position, a grip-operable 120 member pivotally attached to said grip-stop and engageable with said frame when in position of safety, and releasable by grip-compression from engagement with said frame, spring means for moving said firing 125 member to fired position, and affording grip-compression of the grip-operable member, and to return the grip-operable member to engagement with said frame after grip-compression, means engageable with 130

said shiftable slidable means to block the shiftable slidable means in said locking position, and retained, by engagement thereof with said grip-operable member, in said 5 blocking position when said grip-operable member is in position of safety, and movable by said grip-operable member when said member is grip-compressed, and trigger means for shifting said shiftable slid- 10 able means, when said grip-operable member is grip-compressed, out of engagement with said blocking means, and engageable with said sear means to move the sear means to release said firing member for movement 15 to fired position, whereby to retain said shiftable slidable means in said locking position when said grip-operable member is in position of safety, and to release said shiftable slidable means from said locking 20 position when said grip-operable member is grip-compressed.

2. In a firearm, in combination, a sliding breechaction of said firearm, a frame of said firearm comprising a grip-stock, a 25 firing member movable to firing position and to fired position, sear means engageable with said firing member, shiftable slidable means engageable with said sliding breech- 30 action, means for moving said shiftable sliding means to lock said sliding breech- action, and lock said sear means and firing member in firing position, means for moving said shiftable slidable means in a re- 35 verse direction when said firing member is moved to fired position, a grip-operable member pivotally attached to said grip- stock and engageable with said frame when in position of safety, and releasable by grip- compression from engagement with said 40 frame, spring means for moving said firing member to fired position, and affording grip-compression of the grip-operable member, and to return the grip-operable member to engagement with said frame after 45 grip-compression, means engageable with said shiftable sliding means to block the shiftable slidable means in said locking position, and retained, by engagement thereof with said grip-operable member, in said 50 blocking position when said grip-operable member is in position of safety, and movable by said grip-operable member when said member is grip-compressed, and trigger means for shifting said shiftable slid- 55 able means, when said grip-operable member is grip-compressed, out of engagement with said blocking means, and engageable with said sear means to move the sear means to release said firing member for movement 60 to fired position, whereby to retain said shiftable slidable means in said locking position when said grip-operable member is in position of safety, and to release said shiftable slidable means from

said locking position when said grip-oper- 65 able member is grip-compressed.

3. In a firearm, in combination, a frame of said firearm, a firing member movable to firing position and to fired position, sear means engageable with said firing member, 70 shiftable slidable means, means for moving said shiftable slidable means upwardly to lock said sear means and firing member in firing position, means for moving said shiftable slidable means downwardly when said 75 firing member is moved to fired position, a grip-operable member pivotally attached at one end to said grip-stock and engageable at the other end with said frame when in position of safety, and releasable from en- 80 gagement with said frame by grip-compression, spring means for moving said firing member to fired position, and affording grip- compression of the grip operable member, and to return the grip operable member to 85 engagement with said frame after grip compression, means engageable with said shiftable slidable means to block the shiftable slidable means in said upward locking position, and retained, by engagement there- 90 of with said grip-operable member, in said blocking position when said grip-operable member is in position of safety, and movable by said grip operable member when said member is grip-compressed, and trigger 95 means for shifting said shiftable slid- able means, when said grip-operable mem- ber is grip-compressed, out of engagement with said blocking means, and engageable with said sear means to move the sear means 100 to release said firing member for movement to fired position.

4. In a firearm, in combination, a sliding breechaction of said firearm, a frame of said firearm comprising a grip-stock, a fir- 105 ing member movable to firing position and to fired position, sear means engageable with said firing member, shiftable slidable means engageable with said sliding breechaction, means for moving said shiftable slidable 110 means upwardly to lock said sliding breech- action, and lock said sear means and firing member in firing position, means for moving said shiftable slidable means in a reverse direction when said firing member is moved 115 to fired position, a grip-operable member pivotally attached at one end to said grip- stock and engageable at the other end with said frame when in position of safety, and releasable from engagement with said frame 120 by grip-compression, spring means for mov- ing said firing member to fired position, and affording grip-compression of the grip- operable member, and to return the grip- operable member to engagement with said 125 frame after grip-compression, means en- gageable with said shiftable slidable means to block the shiftable slidable means in said

upward locking position, and retained, by engagement thereof with said grip-operable member, in said blocking position when said grip-operable member is in position of safety, and movable when said grip-operable member is grip-compressed, and trigger means for shifting said shiftable slidable means, when said grip-operable member is grip-compressed out of engagement with said blocking means, and engageable with said sear means to release said firing member for movement to fired position.

5. In a firearm, in combination, a frame of said firearm comprising a grip-stock, a firing member movable to firing position and to fired position, a sear member engageable with said firing member, a shiftable slidable member provided with an actuator, a lever-member engaging said actuator and engaging said sear member to move said shiftable slidable member upwardly when said firing member is moved to firing position, to lock said sear member and firing member in firing position, said sear member engaging said firing member and being engageable with said shiftable slidable member to move the shiftable slidable member downwardly when said firing member is moved to fired position, a grip-operable member pivotally attached at one end to said grip-stock and engageable at the other end with said frame when in position of safety, and releasable from engagement with said frame by grip-compression, spring means for moving said firing member to fired position, and affording grip-compression of the grip-operable member, and to return the grip-operable member to engagement with said frame after grip-compression, means engageable with said shiftable slidable member to block the shiftable slidable member in said upward locking position, and retained, by engagement with said grip-operable member, in said blocking position when said grip-operable member is in position of safety, and movable when said grip-operable member is grip-compressed, and trigger means for shifting said shiftable slidable member, when said grip-operable member is grip-compressed, out of engagement with said blocking means, and engageable with said sear member to release said firing member for movement to fired position.

7. In a firearm, in combination, a frame of said firearm comprising a grip-stock, a firing member movable to firing position and to fired position, and provided with a cock-notch and a cam face, a sear member provided with a locking shoulder for engaging said cock-notch and a face for engaging said cam face, and provided with an arm, and provided with a lever-face, and provided with an end face, a shiftable slidable controller provided with an actuator, and provided with a shoulder having an upper surface, and provided with means for receiving a trigger member, and provided with a bottom-side, and provided with an end point, a lever member pivotally attached to said shiftable slidable controller and provided with a face for engaging said actuator, and provided with an end for engaging said lever-face of the sear member to move said shiftable slidable controller upwardly when said firing member is moved to firing position to lock said sear member and firing member in firing position, said face of the sear member when said locking shoulder is disengaged from said cock-notch of the firing member engaging said cam face of the firing member, and said arm of the sear member being engageable with said upper surface of the shoulder of the shiftable slidable controller to move the shiftable slidable controller downwardly when said firing member is moved to fired position.

6. In a firearm, in combination, a sliding breechaction of said firearm, a frame of said firearm comprising a grip-stock, a firing member movable to firing position and to fired position, a sear member engageable with said firing member, a shiftable slidable member engageable with said sliding breechaction; and provided with an actuator, a lever-member engaging said actuator and engaging said sear member to move said shiftable slidable member upwardly when said firing member is moved to firing position to lock said sliding breechaction, and lock said sear member and firing member in firing position, said sear member engaging said firing member and being engageable with said shiftable slidable member to move the shiftable slidable member downwardly when said firing member is moved to fired position, a grip-operable member pivotally attached at one end to said grip-stock and engageable at the other end with said frame when in position of safety, and releasable from engagement with said frame by grip-compression, spring means for moving said firing member to fired position, and affording grip-compression of the grip-operable member, and to return the grip-operable member to engagement with said frame after grip-compression, means engageable with said shiftable slidable member to block the shiftable slidable member in said upward locking position, and retained, by engagement with said grip-operable member, in said blocking position when said grip-operable member is in position of safety, and movable when said grip-operable member is grip-compressed, and trigger means for shifting said shiftable slidable member, when said grip-operable member is grip-compressed, out of engagement with said blocking means, and engageable with said sear member to release said firing member for movement to fired position.

to fired position, a grip-operable member pivotally attached at one end to said grip-stock, and engageable at the other end with said frame when in position of safety, and
5 releasable from engagement with said frame by grip-compression, spring means for moving said firing member to fired position, and affording grip-compression of the grip-operable member, and to return the grip-operable member to engagement with said frame after grip-compression, a blocking member pivotally supported on said grip-stock, and provided
10 with means for engaging said grip-operable member to move the blocking member to engagement with said frame after grip-compression, a blocking member pivotally supported on said grip-stock, and provided with means for engaging said grip-operable member to move the blocking member when said grip-operable member is grip-compressed, and provided with an end-face
15 for engaging said bottom-side and a rear-face for engaging said end-point of the shiftable slidable controller when said grip-operable member is in position of safety, and a trigger member arranged to shift said shiftable slidable controller out of engagement with said blocking member when said grip-operable member is grip-compressed,
20 and engageable with said end-face of the sear member to move said sear member to release said firing member for movement to fired position.
8. In a firearm, in combination, a sliding breechaction of said firearm, a frame of said firearm comprising a grip-stock, a firing member movable to firing position and to fired position and provided with a cock-notch and a cam face, a sear member provided with a locking shoulder for engaging said cock-notch and a face for engaging said cam face, and provided with an arm, and provided with a lever-face, and provided with an end-face, a shiftable slidable controller engageable with said sliding breechaction, and provided with an actuator, and provided with a shoulder having an upper surface and provided with means for receiving a trigger member, and provided
35 with a bottom-side and an end-point, a lever member pivotally attached to said shiftable slidable controller and provided with a face for engaging said actuator, and provided with an end for engaging said lever-face of the sear member, to move said shiftable slidable controller upwardly when said firing member is moved to firing position to lock said sliding breechaction, and lock said sear member and firing member in firing position,
40 said face of the sear member when said locking shoulder is disengaged from said cock-notch of the firing member engaging said cam face of the firing member, and said arm of the sear member being engageable with said upper surface of the shoulder of the shiftable slidable controller to move the controller downwardly when said firing member is moved to fired position, a grip-operable member pivotally attached at one
45 end to said grip-stock and engageable at the other end with said frame when in position of safety, and releasable from engagement with said frame by grip-compression, a blocking member pivotally supported on said grip-stock, and provided with means for engaging said grip-operable member to move the blocking member when said grip-operable member is grip-compressed, and provided with an end-face for engaging said bottom-side and a rear-face for engaging said end-point of the shiftable slidable controller when said controller is in said upward locking position and said grip-operable member is in position of safety, and a trigger member arranged to shift said shiftable slidable controller out of engagement with said blocking member when said grip-operable member is grip-compressed, and engageable with said end-face of the sear member to move said sear member to release said firing member for movement to fired position.
9. In a firearm, in combination, a frame of said firearm comprising a grip-stock, a firing hammer movable to firing position and to fired position, and provided with a cock-notch and an eccentric cam face, a sear member provided with a locking shoulder for engaging said cock-notch and a face for engaging said eccentric cam face, and provided with an arm, and provided with a lever-face, and provided with an end-face, a shiftable slidable controller provided with a spring operated actuator, and provided with a shoulder having an upper surface, and provided with means for receiving a trigger member, and provided with a bottom-side and an end-point, a lever-member pivotally attached to said shiftable slidable controller and provided with a face for engaging said actuator, and provided with an end for engaging said lever-face of the sear member, to move said shiftable slidable controller upwardly to lock said sear member and firing hammer in firing position, said face of the sear member when said locking shoulder is disengaged from said cock-notch of the firing hammer engaging said eccentric cam face of the firing hammer, and said arm of the sear member being engageable with said upper surface of the shoulder of the shiftable slidable controller to move the controller downwardly when said firing hammer is moved to fired position, a grip-safety member pivotally attached at one end to said grip-stock and engageable at the other end with said frame when in position of safety, and releasable from engagement with said frame by grip-compression, a blocking member pivotally supported on said grip-stock, and provided with means for engaging said grip-safety member to move the blocking member when said grip-safety member is grip-compressed, and provided with an end-face for engaging said bottom-side and a rear-face for engaging said end-point of the shiftable slidable controller when said controller is in said upward locking position and said grip-safety member is in position of safety, and a trigger member arranged to shift said shiftable slidable controller out of engagement with said blocking member when said grip-safety member is grip-compressed, and engageable with said end-face of the sear member to move said sear member to release said firing member for movement to fired position.

- supported on said grip-stock, and provided with a rear-face for engaging said grip-safety member to move the blocking member when said grip-safety member is grip-compressed, and provided with an end-face for engaging said bottom-side and a rear-face for engaging said end-point of the shiftable slidable controller when said controller is in upward locking position and 5 said grip-safety member is in position of safety, means for preventing disengagement of said grip-safety member at its upper end from said frame by rearward movement of the grip-safety member, and preventing 10 rearward movement of said blocking member when said grip-safety member is in position of safety, a firing spring, pivotal means for connecting said firing hammer to said blocking member, and providing a 15 stem and a seat and an abutment for said firing spring, and a trigger member received by said shiftable slidable controller and pivotally attached thereto, and movable forwardly, and by pull thereon movable rearwardly to shift said shiftable slidable controller out of engagement with said blocking member when said grip-safety member is grip-compressed, and provided with an 20 end-face for engaging said end-face of the sear member to move the sear member to release said firing hammer for movement to fired position. 25
10. In a firearm, in combination, a sliding breechaction of said firearm, a frame of 30 said firearm comprising a grip-stock, a firing hammer movable to firing position and to fired position, and provided with a cock-notch and an eccentric cam face, a sear member provided with a locking shoulder for engaging said eccentric cam face, and provided with an arm, and provided with an end-face, a shiftable slidable controller engageable with said sliding breechaction and provided with a spring operated actuator, 35 and provided with a shoulder having an upper surface, and provided with means for receiving a trigger member, and provided with a bottom-side and an end-point, a lever member pivotally attached to said 40 shiftable slidable controller and provided with a face for engaging said actuator, and provided with an end for engaging said lever-face of the sear member, to move said shiftable slidable controller upwardly to 45 lock said sliding breechaction, and lock said sear member and firing hammer in firing position, said face of the sear member when said locking shoulder is disengaged from said cock-notch of the firing hammer and 50 gaging said eccentric cam face of the firing hammer, and said arm of the sear member being engageable with said upper surface of the shoulder of the shiftable slidable controller to move the controller downwardly 55 when said firing hammer is moved to fired 60 position, a grip-safety member pivotally attached at one end to said grip-stock and engageable at the other end with said frame when in position of safety, and releasable from engagement with said frame by grip-compression, a blocking member pivotally supported on said grip-stock, and provided with a rear-face for engaging said grip-safety member to move the blocking member 65 when said grip-safety member is grip-compressed, and provided with an end-face for engaging said bottom-side and a rear-face for engaging said end-point of the shiftable slidable controller when said controller is in upward locking position and said grip-safety member is in position of safety, means for preventing disengagement of said grip-safety member at its upper end from said frame by rearward movement of the grip-safety member, and preventing 70 rearward movement of said blocking member when said grip-safety member is in position of safety, a firing spring, pivotal means for connecting said firing hammer to said blocking member, and providing a stem 75 and a seat, and an abutment for said firing spring, and a trigger member received by said shiftable slidable controller and pivotally attached thereto, and movable forwardly, and by pull thereon movable rearwardly to shift said shiftable slidable controller out of engagement with said blocking member when said grip-safety member is grip-compressed, and provided with an end-face for engaging said end-face of the 80 sear member to move the sear member to release said firing hammer for movement to fired position. 85
11. In a firearm, in combination, a frame of said firearm, a firing member movable to firing position and to fired position, a grip-compressible member engageable with said frame, and releasable from said engagement by grip-compression, a blocking member movable by engagement thereof with 90 said grip-compressible member when the grip-compressible member is grip-compressed, and spring means for moving said firing member to fired position, and affording grip-compression of the grip-compressible member, and to return the grip-compressible member to engagement with said frame after grip-compression. 95
12. In a firearm, in combination, a frame of said firearm, a firing member movable to 100 firing position and to fired position, a grip-compressible member engageable with said frame, and releasable from said engagement by grip-compression, a blocking member movable by engagement thereof with said grip-compressible member when said grip-compressible member is grip-compressed, and spring means operatively connected to said firing member and to said blocking member, for moving said firing member to 105 fired position. 110
13. In a firearm, in combination, a frame of said firearm, a firing member movable to 115 firing position and to fired position, a grip-compressible member engageable with said frame, and releasable from said engagement by grip-compression, a blocking member movable by engagement thereof with said grip-compressible member when said grip-compressible member is grip-compressed, and spring means operatively connected to said firing member and to said blocking member, for moving said firing member to 120 fired position. 125
14. In a firearm, in combination, a frame of said firearm, a firing member movable to 130 firing position and to fired position, a grip-compressible member engageable with said frame, and releasable from said engagement by grip-compression, a blocking member movable by engagement thereof with said grip-compressible member when said grip-compressible member is grip-compressed, and spring means operatively connected to said firing member and to said blocking member, for moving said firing member to fired position. 135

fired position, and affording grip-compression of the grip-compressible member, and to return the grip-compressible member to engagement with said frame after grip-compression.

13. In a firearm, in combination, a frame of said firearm, a firing member movable to firing position and to fired position, a grip-compressible member engageable with said frame, and releasable from said engagement by grip-compression, a blocking member movable by engagement thereof with said grip-compressible member when said member is grip-compressed, a spring, and means for connecting said firing member to said blocking member and providing a stem and a seat and an abutment for said spring.

14. In a firearm, in combination, a frame of said firearm, a firing member movable to firing position and to fired position, a grip-compressible member engageable with said frame, and releasable from said engagement by grip-compression, a blocking member movable by engagement thereof with said grip-compressible member when the grip-compressible member is grip-compressed, a spring, and pivotal means for connecting said firing member to said blocking member, and providing a stem and a seat and an abutment for said spring.

15. In a firearm, in combination, a frame of said firearm comprising a grip-stock, a firing member movable to firing position and to fired position, a grip-safety member pivotally attached to said grip-stock and engageable with said frame, and releasable from engagement with said frame by grip-compression, a blocking member engaging said grip-safety member for movement thereby when the grip-safety member is grip-compressed, a rod pivotally attached at one end to said firing member and pivotally attached at the other end to said blocking member, and a spring surrounding said rod, and seated at one end of said rod and abutting the other end of said rod.

16. In a firearm, in combination, a frame of said firearm comprising a grip-stock, a firing hammer movable to firing position and to fired position, a grip-safety member pivotally attached at one end to said grip-stock and engageable at the other end with said frame, and releasable from engagement with said frame by grip-compression, a blocking member engaging said grip-safety member for movement thereby when the grip-safety member is grip-compressed, a rod pivotally attached at the upper end to said firing hammer and pivotally attached at the lower end to said blocking member, and a spring surrounding said rod and seated upon the lower pivotal attachment of said rod and abutting the upper pivotal attachment of said rod; a line from the center of the upper pivotal attachment

of said rod through the center of the lower pivotal attachment of said rod passing, when said firing hammer is in firing position, to the rear of the center of pivotal attachment of said grip-safety member to said grip-stock, and passing, when said firing hammer is in fired position to the front of the center of pivotal attachment of said grip-safety member to said grip-stock.

17. In a firearm, in combination, a frame of said firearm, a firing member movable to firing position, and to fired position, sear means engageable with said firing member, means for moving said firing member to fired position, shiftable slidable means for locking said sear member and firing member in firing position, grip-compressible movable means operatively supported by said frame for blocking said shiftable slidable means in said locking position, and trigger means for primarily shifting said shiftable slidable means to release the same from said blocking means, and for subsequently moving said sear means to release said firing member for movement to fired position.

18. In a firearm, in combination, a sliding breechaction of said firearm, a frame of said firearm, a firing member movable to firing position and to fired position, sear means engageable with said firing member, means for moving said firing member to fired position, shiftable slidable means for locking said sliding breechaction, and locking said sear means and firing member in firing position, grip-compressible movable means operatively supported by said frame for blocking said shiftable slidable means in said locking position, and trigger means for primarily shifting said shiftable slidable means to release the same from said blocking means, and for subsequently moving said sear means to release said firing member for movement to fired position.

19. In a firearm, in combination, a frame of said firearm comprising a grip-stock, a firing member movable to firing position and to fired position, sear means engageable with said firing member, means for moving said firing member to fired position, shiftable slidable means for locking said sear member and firing member in firing position, grip-compressible movable means pivotally supported on said grip-stock for blocking said shiftable slidable means in said locking position, and trigger means for primarily shifting said shiftable slidable means to release the same from said blocking means, and for subsequently moving said sear means to release said firing member for movement to fired position.

20. In a firearm, in combination, a sliding breechaction of said firearm, a frame of said firearm comprising a grip-stock, a firing member movable to firing position and to fired position, sear means engageable with

said firing member, means for moving said firing member to fired position, shiftable slidable means for locking said sliding breechaction, and locking said sear means and firing member in firing position, grip-compressible movable means pivotally supported on said grip-stock for blocking said shiftable slidable means in said locking position, and trigger means for primarily shifting said shiftable slidable means to release the same from said blocking means, and for subsequently moving said sear means to release said firing member for movement to fired position.

JOHN D. PEDERSEN.
